UNITED STATES PATENT OFFICE.

SAMUEL WESTERFIELD, OF NEW YORK, N. Y.

DESIGN FOR AN ELECTRIC TABLE LAMP.

Application filed April 25, 1927. Serial No. 21,713. Term of patent 3½ years.

To all whom it may concern:

Be it known that I, SAMUEL WESTERFIELD, a citizen of the United States, residing at New York, in the county and State of New York, have invented a new, original, and ornamental Design for an Electric Table Lamp, of which the following is a specification, reference being had to the accompanying drawing, forming part thereof.

Figure 1 is a front view of a table lamp, showing my new design; and,

Figure 2 is a flattened or spread out form of the shade forming a part of the design shown in Figure 1 before being assembled.

I claim:

The ornamental design for an electric table lamp, as shown.

SAMUEL WESTERFIELD.
